UNITED STATES PATENT OFFICE.

CHARLES GILBERT HAWLEY, OF CHICAGO, ILLINOIS, ASSIGNOR TO LOCOMOTIVE FIRE-
BOX COMPANY, OF CHICAGO, ILLINOIS, A CORPORATION OF DELAWARE.

MACHINE FOR FORMING, BENDING, FOLDING, AND SHAPING HEAVY METAL SHEETS.

Application filed February 6, 1925. Serial No. 7,230.

My invention relates to improvements in machines for forming, bending, folding and shaping heavy metal sheets such as parts of steam boilers, and has particular reference 5 to that kind of a machine shown in my prior Patent No. 1,488,494 of April 1, 1924, especially designed for making what is now well known as the Nicholson thermic siphon and the like.

One of the objects of the present invention is to simplify and improve in general, not only the construction of such a machine but also the operation thereof.

Another object of the invention is to provide an improved connection between the associated folding wings and between said wings and associated spotting columns, so that said wings will operate in unison and will engage, with equal pressures, the sheet 20 of metal being operated upon and will exert not only a folding action but a certain pinching action better to form the bulge in the folded sheet as will later appear.

A further object of the invention is to so 25 construct the machine that instead of forming the bulge along the entire length of the folded sheet as heretofore and thereafter flattening out one end of the bulge manually to provide that portion which subsequently 30 becomes the end flange of the body, said bulge is made to terminate short of said end which is left flat in the forming of the siphon, the excess metal being displaced upwardly, thus reducing the cost of production 35 and leaving the sheet in a better condition for forming the end flange.

Still a further object of the invention is to provide a simple and efficient means for stripping or removing the folded or formed 40 metallic sheet from the forming horse or mandrel.

The invention generally consists in the form, arrangement, construction and co-operation of the parts, whereby the above 45 mentioned objects, together with others that will hereinafter appear, are attainable and the invention will be more readily understood by reference to the accompanying drawings which illustrate what I consider at the present time to be the preferred embodiment thereof.

In said drawings:

Fig. 1 is a view in front end elevation of

a machine of the kind mentioned, embodying my invention.

55

Fig. 2 is a top plan view thereof.

Fig. 3 is a vertical sectional view on the line 3—3 of Fig. 2 and shows the machine in side elevation.

Fig. 4 is a detail vertical sectional view 60 on an enlarged scale as taken on the line 4—4 of Fig. 3.

Fig. 5 is a detail view of a winding pulley or sheave embodied in my improved machine, with parts broken away to more clearly 65 show the manner in which an associated link chain is connected thereto and which will be more fully referred to later.

Fig. 6 is an enlarged detail horizontal sectional view through a part of the stripping 70 mechanism, the plane of the section being indicated by the line 6—6 of Fig. 3.

Fig. 7 is an enlarged detail vertical sectional view through another part of the stripping mechanism, the plane of the section being indicated by the line 7—7 of 75 Fig. 3.

Fig. 8 is a detail horizontal sectional view on an enlarged scale as taken on the line 8—8 of Fig. 3 and shows in plan elevation, 80 the means for hingedly connecting the folding wings together.

Figs. 9, 10 and 11 are detail perspective views of parts shown in Fig. 8 and which will be more specifically referred to later.

85

Fig. 12 is a perspective view of a portion of the forming horse or mandrel with the formed sheet thereon.

Figs. 13, 14 and 15 are detail vertical sectional views on an enlarged scale, as taken 90 on the lines 13—13, 14—14 and 15—15, respectively of Fig. 12.

Fig. 16 is a detail horizontal sectional view as taken on the line 16—16 of Fig. 12.

Fig. 17 is a perspective view of one of 95 the forming blocks associated with one of the forming wings.

Fig. 18 is a view in front end elevation of that portion of the folded sheet shown in the right hand end of Fig. 12.

100

Although my improved machine is adapted for many uses and may be advantageously employed in the manufacture of articles of different forms and shapes, the machine is especially adapted for forming heavy metallic sheets such as boiler plate into a trough-

105

shaped article and I will describe the same with reference to the manufacture of such an article but this is to be taken as by way of illustration only and hence I do not wish it to be construed as a limitation.

The trough-shaped article above referred to is what is now well-known as a Nicholson thermic siphon which is adapted as a water circulating and steaming element in boilers and especially in locomotive boilers. As such siphons are of a comparatively large size the sheet employed for the formation thereof is relatively heavy so that the machines for forming them and as herein illustrated are therefore of a comparatively large size.

As herein shown I provide a pit 1 in a floor 2 or the like upon which the structural work of the improved machine is erected. In the median line of the pit I provide a vertically disposed mandrel or horse 3, the bottom end 4 of which is firmly attached or anchored to the bottom wall or floor 5 of the pit. The top end part of the said mandrel extends into a plane above that of the floor 2 and is formed to provide an enlarged cylindrical horizontally disposed ridge portion 6, which terminates short of the front end of the mandrel and tapers off to meet the sides thereof as best shown at 6^a in Figs. 12 and 16. The cross sectional shape of the mandrel or horse is such as determines the cross-sectional shape of the finished article.

Positioned a suitable distance above the horse and extending transversely with respect thereto are a plurality of beams 7. Said beams are secured at their ends upon stringers 8 and 9 respectively, which extend parallel with, but are equally spaced upon each side of the plane of said horse. Said stringers are suitably supported upon the top ends of upright columns or posts 10 and 11 which are secured to and are braced from the floor 2 adjacent the side walls of the pit 1. To one side of the structural work just described and suitably supported at one end upon the columns 11 is a platform 12 arranged in a horizontal plane below that of the beams 7. The other end of said platform is supported on shorter upright columns 13. This platform is the control platform for the machine, which as before mentioned is of a considerable size and, so that the operator may easily gain access to said platform, I provide a ladder 14 therefor. About the platform 12 is arranged a guard railing 15 for the operator.

16 and 17 indicate, respectively, two horizontal shafts which are equally spaced, one on each side of the plane of and extending parallel with the horse or mandrel 3, said shafts being journaled in pillow blocks 16^a and 17^a, respectively, mounted on the transverse beams 7. On the shaft 16 are secured longitudinally spaced front and rear

single pulleys or drums 18-18 and on the shaft 17 are secured longitudinally spaced front and rear pulleys 19 and 20, respectively, arranged in pairs as shown in Fig. 2. All of the pulleys 18, 19 and 20 are of the same size. 21 indicates a larger pulley which is secured to the shaft 17 at a point substantially midway between the pairs of pulleys 19 and 20. This last mentioned pulley is operatively connected by a cable 22 to the winding drum of a hoisting engine 23 mounted on the platform 12. Said hoisting engine is driven from an electric motor 24 (also located on said platform), through a gear reduction train and clutch 25, which clutch may be readily actuated by a control lever 26 arranged adjacent a controller switch 27 for said motor. Secured to the pulleys of each pair of pulleys 19 and 20 are the ends of coacting link chains 28 and 29, the chains 28-28 leading off from the bottom of the pulleys 20 and being trained over the top of the pulleys 18. In Fig. 5 I have illustrated one of the pulleys 19 and the manner of securing the associated chain 28 thereto. Said pulley is a grooved pulley and in the peripheral groove thereof is located a block 30 which includes a threaded stem 31. This stem extends radially inward and through the peripheral part of the pulley to receive a nut which securely positions said block in said groove. In said block is secured the threaded part of a clevis 32 to which the end link of the chain 28 is secured. The chains 28 are secured to the pulleys 20 in the same manner.

The opposite ends of the chains 28 and 29 are connected to pairs of lugs 33 and 34, respectively, secured to wings 35 and 36, respectively. Said wings are heavy or weighty members and perform their function by falling or dropping upon the metal sheets or plates to be folded. The chains 28-29 are utilized to control the dropping of the wings and also for their elevation to that position from which they are dropped. The wings may be held in this last mentioned position when the machine is not in active operation, independent of the chains 28-29 and to that end I provide the following construction. On said wings are secured inner and outer pairs of eyes 37-38 arranged near the ends of said wings. Said eyes are adapted to be engaged by sets of hooks 39-39 which are fixed to the ends of shafts 40-40. These shafts extend parallel with the shafts 16 and 17 and are journaled in suitable bearings mounted on the transverse beams 7. The hooks 39 of each set are all operatively connected together by means of pivotally connected links 41-41 as shown in Fig. 1 so that when movement is imparted to one hook, a similar movement is imparted to all of said hooks which normally hang pendant. When said wings are in

their idle or inoperative position, the hooks 39 will engage the eyes 37-38, thereby removing the weight thereof from the chains 28, 29. When it is desired to bring the wings into operative position the hooks are removed from engagement with the eyes on said wings.

As best illustrated in Fig. 4, the wings 35 and 36 comprise heavy flat metallic sheets or plates 42-42, to the inner or opposed surfaces of which are secured wooden filler members or planks 43-43 having metallic face or wear resisting plates 44. Spaced somewhat from the contiguous edges of said wings are pinch bars 45-45 which are suitably secured in guides 46-46 in turn fixed to said wings as shown, the purpose of said pinch bars being to directly engage the sheet being formed and to co-operate with the mandrel to govern the form imparted to the sheet by the operation of the machine. The pinch bars 45 and their guides 46 terminate in substantially the plane of the tapered portions 6^a of the ridge 6 and abut with forming blocks 46^a secured to the inner surfaces of said wings at their front ends. These forming blocks are provided with tapered or bevelled corner portions 46^b which coact with the tapered portions of the ridge 6 to gradually flatten out the bulge in the folded sheet, as will later appear.

The wings 35 and 36 are operatively connected together against undesirable separation in a horizontal plane by means of the following construction: Secured to the contiguous edges of said wings are bracket members 47, there preferably being twelve of said brackets secured to each wing and disposed thereon as shown in Fig. 3. The said brackets each include a plate part 47^a which engages with the outer face of the associated wing and is secured thereto in any suitable manner, and a right angular disposed part 47^b which overhangs the edge of said plate to terminate in longitudinally spaced bearing sleeves 47^c-47^c as best shown in Fig. 8. The brackets 47 at the front and rear ends of the wings are operatively connected together by links 48 (see Figs. 8 and 9) each of which includes front, rear and intermediate upwardly arched cross bars 48^a-48^b and 48^c, respectively, between which the sleeves 47^c of the brackets 47 engage and are pivotally secured by pins 49 as shown in Fig. 8. These links 48 may be conveniently termed "spotting" links because they are each provided at one end on their bottom side with a longitudinally extending tongue 50 which is adapted to enter a groove 6^a in the ridge portion 6 of the horse 3 when the wings are moving into their operative position with respect to the horse or mandrel 3. In the initial movement of said wings the tongues 50 of both links 48 enter the end portions of the groove 6^a in the ridge of the

mandrel and act to hold the top end of the mandrel against lateral movement and at the same time insure registration or alignment of the ends of said wings with respect to said mandrel or horse.

The brackets 47 between the endmost brackets 47 are arranged in longitudinally spaced pairs, the pairs on one wing being disposed opposite those on the other wing. The brackets 47 of the first pair of brackets, spaced rearwardly form the "spotting" links 48 at the end part of the wings 35-36 are operatively connected together by center links 51-52 somewhat similar to the links 48 before referred to except that said center links have no spotting tongues. Each link 51-52 has an arched transverse body portion 51^a-52^a respectively with longitudinal extensions 51^b-52^b as best shown in Fig. 8, the ends of each body portion terminating in sleeves 51^c-52^c respectively adapted to engage between and align with the bearing sleeves 47^c of the associated brackets 47. Pins 53-53 connect said link and sleeve parts together as shown in Fig. 8, end links 51^d-52^d arranged in pairs connecting the ends of the pins 53-53 together. In this instance the adjacent end links 51^d-52^d of said links 51-52 are spaced relatively close together for a purpose to appear later. The ridge portion 6 of the mandrel begins to narrow down or taper transversely as at 6^a in the manner before mentioned as it approaches the plane of said links, and the metal of the plate being operated upon at this point and from thereon out to the front end of the folded sheet is displaced upwardly by the forming blocks 46^a and this upward displacement is taken care of or is permitted because of the transverse arched portions of the links 48, 51 and 62, which portions are spaced a distance above said ridge sufficient to accommodate said upward displacement as best shown in Figs. 14 and 15.

The brackets 47 of each pair of the next four pair of brackets are spaced apart by bifurcated links 55, one of which is shown in perspective in Fig. 11, and interposed between the sleeves 47^c of said brackets are connecting links 56 each of which has end extensions 56^a similar to the extensions of the links 51-52 before mentioned. Said links 56 are straight instead of arched and one of said links is shown in perspective in Fig. 10. Pins 57 pivotally connect the links 55-56 with the sleeves 47^c of the associated brackets 47, and the ends of said pins are connected by straight end links 57^a as best shown in Fig. 8.

58 indicate a plurality of upright guide posts or spotting columns, the top ends of which have sliding guiding bearings in bearing blocks 59 secured to the transverse beams 7 in the plane of the horse 3. The bottom end of the foremost spotting column 58 ex-

tends in between and is pinned to the adjacent end links 51^a—51^d associated with the center links 51—52 as shown in Fig. 8, while the bottom ends of the remainder of said spotting columns are pinned to the bifurcated links 55 of the associated brackets 47 as shown at the right hand end of said Fig. 8.

- Associated with the machine thus far described is a means for removing or stripping 10 the formed sheet from the horse and such means is as follows: In the plane of the horse and spaced a suitable distance rearwardly thereof is an upright column 62 in the form of a channel bar, which column 62 is 15 suitably braced by angularly disposed members 63 as shown in Figs. 2 and 3. Said column is connected to the horse or mandrel by means of parallel spaced rails 64 upon which travel the wheels 65 of a carriage 66. 20 To said carriage is fixed the rear end of an inverted U-shaped stripper member 67. The front end of this stripper member which normally rests upon a rearward extension 6^b of the ridge portion 6 of the horse 3, as 25 shown in Fig. 3 is slotted longitudinally for a predetermined distance as indicated at 67^a in Figs. 2, 3 and 7 for a purpose later to appear. The carriage 66 includes two rearwardly extending arms 66^a (see Figs. 3 and 6) between which is journaled a double grooved pulley 68. Mounted on the column 62 below the rails 64 is a reversible motor driven winding drum 69, the operation of 30 which is controlled from a controller switch 35 70 located on the platform 12. Mounted on the rear end of the horse 3 in the plane of said winding drum is a bearing block 71 in which a pulley 72 is journaled. Also secured to the rear end of said horse is an 40 upright cable stand or arm 73 which stand or arm is bifurcated so as to straddle the extension 6^b of the ridge portion 6 and permit the movement of the stripper member as best shown in Fig. 7. A cable 74 is connected at one end to the cable stand 73 and passes over the top of the pulley 68 in one groove thereof and then passes forwardly to be trained about the pulley 72 journaled in the bracket 71. From this pulley, said 45 cable extends rearwardly to be wound a few turns about the motor driven winding drum 69 and then passes under the bottom of the pulley 68 in the other groove thereof, the (other) end of said cable being fixed to the top end of the column 62 as shown in Fig. 3. From the foregoing, it is apparent that 50 when the drum 69 is driven in one direction, the stripper member is moved forwardly of and onto the horse so as to strip the folded sheet therefrom and that when said drum is driven in the other direction the stripper member is withdrawn rearwardly from the horse into the position shown in said Fig. 3. Should it be desired at any time to impart 55 a limited forward movement to the stripper

member when the wings are in their operative position, this is readily permitted because of the slot 67^a in the stripper, which will straddle the tongue 50 on the rear end link 48, at this time engaged in the slot in 70 the ridge of the mandrel.

The metal sheet or plate to be formed is indicated at 75 in Figs. 1 and 2, respectively, said plate being substantially kite-shaped as shown in dotted lines in Fig. 2. Said plate is positioned on the ridge portion 6 of the horse and at opposite ends thereof are provided pins 75^a (see Fig. 2) which extend into the groove 6^a of the ridge portion 6 of the horse to center and hold the sheet with 80 respect thereto.

It will be understood of course, that the sheet cannot be positioned on the mandrel or ridge portion until the wings 35 and 36 have been elevated into the horizontal position shown in full lines in Fig. 2 and in which position they are normally held by the hooks 39 as before described. When the sheet has been thus positioned the hooks 39 are removed from engagement with the eyes 37—38 of the wings, the weight of said wings now being sustained by the chains 28, 29 associated with the drum of the hoisting engine 23, which drum is now locked by the clutch 25 thereof. When the clutch is released by the lever 26, the hinged wings will drop under their own weight to engage the sheet or plate 75.

The engagement or settling of the weight of the wings upon said sheet serves to bend 100 it, and as is apparent the accelerating fall or movement of the heavy wings results in closing them together against the horse, as shown in dotted lines in Fig. 1. This practice might be followed in the case of articles to be folded from comparatively thin sheets, "thin" being used in this instance relative to the strength of the sheet and the weight of the wings which are allowed to fall upon it. In dealing with sheets of relatively 105 heavy or thick stocks and to avoid unnecessary jars or shocks, I prefer to start by first positioning the sheet on the mandrel and then slowly lowering the wings by letting the clutch 25 slip. The first action of the 110 wings thus allowed to slowly settle on the sheet, is to bend it so that its two sides or halves are bent at about a right angle to one another. This having been accomplished, the wings are again lifted by means of the hoisting engine 23 and after said position is reached, they are held therein by the clutch 25. The clutch is then released and the heavy wings are allowed to drop on the 115 partially bent sheet. This operation or movement is repeated as many times as may be necessary to complete the folding of the sheet around the mandrel and horse. In 120 actual practice only a few of the heavy blows thus delivered are required.

In this last mentioned part of the movement of the side wings and as they approach the mandrel, the longitudinal median portion of the sheet 75 is bent or folded about and follows the formation of the ridge to provide the major portion of the bulge 75^a of the siphon. During this part of the movement of the wings, and because of the positions which the bars 45 bear with respect to the hinge pins 49, 53 and 57, said bars will swing into the vertical planes of said hinge pins and will forcibly engage parts of the sheet just below the plane of the bottom of ridge 6. However, due to the long lever effect of the free ends of the wings a peculiar action takes place in that the wings try to fulcrum about said bars as an axis which, of course, is resisted by the links connecting the wings together. Due to this resistance the bars 45 move through said planes of said hinge pins and the portions of said sheet between said bars and the undersides of the projecting parts of the ridge are pinched and displaced upwardly to produce ledges 75^b which connect said bulge with the side walls of the siphons. Said ledges form the support upon which the bricks of the fire-arch rest when the siphon is installed in a firebox. It will be apparent that the link arrangement between the side wings provide not only a hinged connection for said wings, but also provide for the pinching or displacing of portions of the sheet to form said ledges. As before mentioned, the bulge portion 75^a terminates short of the front end of the horse 6 and from thereon the excess metal in the middle portion of said front end of the sheet is displaced upwardly into a plane above that of the ridge as shown at 75^c (see Fig. 12) by the forming blocks 46^a, the tapered recesses 46^b therein, so coacting with the tapered portions 6^b of the ridge 6 as to gradually flatten out the bulge and merge the same into the side walls of the formed sheet as best shown in Figs. 12 to 16 inclusive of the drawings. This upward displacement is readily permitted by the links 48, 51 and 52 because of the transverse arched or curved formation of the same as before described. By this construction it is not necessary to form the bulge the entire length of the sheet and to thereafter manually flatten out the same so that the end flange of the finished siphon may be produced. In the elimination of this step in forming the siphon, a great saving in time and labor in making the siphon is attained.

From this description it is apparent that I am able in a very few minutes to fold the great sheet of steel from which a Nicholson thermic siphon is formed. The pre-shaped flat sheet clearly appears in dotted lines in Fig. 3 and in full lines in Fig. 12, and the cross-sectional shape thereof when folded appears in Figs. 1, 4, 13, 14 and 15, a front

end view of the same appearing in Fig. 18.

After the sheet has thus been formed, the wings 35-36 are lifted by means of the hoisting engine 23 into the full line position shown in Fig. 1. Said wings are then secured in this position by means of the hooks 39, thus taking the strain off the hoisting engine. The operator on the platform next actuates the controller switch 70 to drive the drum 69 to wind up that part of the cable 74 connected to the stand 73 and to unwind or pay off that end of the cable connected to the column 62. This moves the stripper element 67 forwardly in close engagement with the ridge portion 6^a and pushes the folded article off the front end of the horse. The winding drum 69 is then driven in the other direction to restore the stripper member to its original or withdrawn position which is the position it is normally arranged in, as shown in Fig. 3.

By the arrangement of the brackets and links relative to the wings, I provide a strong and rigid hinge connection between said links and wings and at the same time, because of the relative arrangement between said hinge connection and bars 45, said bars have a pinching action which quickly and accurately forms the ledge portions 75^b in the shaped sheet. Again the spotting columns or posts associated with several of said links together with their connection to the wings will insure uniformity of movement of said wings so that the folded sheet will truly conform to the horse or mandrel. Again the tongues 50 of the link 48 not only insure registration of the wings with respect to the horse but also act to so connect said horse and wings together in a manner preventing lateral swaying or wabbling of the ridge portion of the horse.

Inasmuch as the disclosure herein will readily suggest to others skilled in the art to which this invention appertains, various modifications thereof, I do not wish to be limited to the specific construction herein shown and described except as only may be necessary by limitations in the hereunto appended claims.

I claim as my invention:

1. A device of the kind described embodying therein a mandrel, a pair of swingable members, a plurality of spotting columns for locating and holding said swingable members with respect to said mandrel, brackets secured to said swingable members, and means for operatively connecting said brackets together, said last mentioned means being secured to said spotting columns.

2. A device of the kind described embodying therein a mandrel, a pair of swingable members, a plurality of spotting columns for locating and holding said swingable members with respect to said mandrel, brackets secured to said swingable members, a link

115

120

125

130

member secured to the bottom end of each spotting column and means connecting said brackets with the ends of said link members.

3. A device of the kind described embodying therein a mandrel, a pair of swingable members, a plurality of spotting columns for locating and holding said swingable members with respect to said mandrel, bracket members arranged in pairs and fixed to said swingable members, and link members fixed to the bottom ends of said spotting column, said brackets being pivotally connected to the ends of said link members.

4. A device of the kind described embodying therein a mandrel, a pair of swingable members, a plurality of spotting columns for locating and holding said swingable members with respect to said mandrel, bracket members arranged in pairs and fixed to said swingable members, link members fixed at their middle to the bottom ends of said spotting columns, some of said link members including transversely arched cross bars to the ends of which said brackets are pivotally connected.

5. A device of the kind described embodying therein a mandrel, a pair of swingable members, a plurality of spotting columns for locating and holding said swingable members with respect to said mandrel, bracket members arranged in pairs and fixed to said swingable members, link members fixed at their middle to the bottom ends of said spotting columns, some of said link members including transversely arched cross bars to the ends of which said brackets are pivotally connected, one of said link members and said mandrel having interengaging parts which assist said columns to locate said swingable members with respect to said mandrel.

6. A device of the kind described embodying therein a mandrel having a groove therein, a pair of swingable members, a plurality of spotting columns for locating and holding said swingable members with respect to said mandrel, bracket members arranged in pairs and fixed to said swingable members, link members fixed at their middles to the bottom end of said spotting columns, the ends of said link members being pivotally connected to said bracket members, one of said link members having a tongue adapted to enter the groove in said mandrel to assist the spotting columns in locating said swingable members with respect to said mandrel.

7. A device of the kind described embodying therein a mandrel, a superstructure arranged above the mandrel, a pair of swingable members, a plurality of members guided for sliding movement in said superstructure and operatively connected to said swingable members to locate the same with respect to said mandrel, means including flexible members connected to said swingable members for imparting movement to them, pulleys on

said superstructure over which said flexible members pass, means for winding and releasing said flexible members, and means on said structure adapted to engage with said swingable members for supporting them in a predetermined position independent of said last mentioned means.

8. A device of the kind described embodying therein a mandrel, a superstructure arranged above the mandrel, a pair of swingable members, a plurality of members guided for sliding movement in said superstructure and operatively connected to said swingable members to locate the same with respect to said mandrel, means including flexible members connected to said swingable members for imparting movement to them, pulleys on said superstructure over which said flexible members pass, means for winding and releasing said flexible members, and a plurality of hook members on said superstructure adapted to engage parts of said swingable members for supporting them in a predetermined position independent of said last mentioned means.

9. A device of the kind described embodying therein a mandrel, a superstructure arranged above the mandrel, a pair of swingable members arranged below the superstructure and capable of movement toward and away from the mandrel, means including flexible members connected to said swingable members for operating them, pulleys on said superstructure over which said flexible members pass, means for winding and releasing said flexible members, and means on said superstructure capable of being moved into engagement with said swingable members to support them in a position above the mandrel independent of the said means for winding and releasing said flexible members.

10. A device of the kind described embodying therein a mandrel, a superstructure arranged above the mandrel, a pair of swingable members arranged below the superstructure and capable of movement toward and away from the mandrel, means including flexible members connected to said swingable members for operating them, pulleys on said superstructure over which said flexible members pass, means for winding and releasing said flexible members, eye members on said swingable members, and hooks on said superstructure so arranged as to simultaneously engage said eyes to support said swingable members in a position parallel with said superstructure, said hooks also being capable of being actuated to be simultaneously disengaged from said eyes.

11. A device of the kind described embodying therein a mandrel, a pair of swingable members, capable of movement toward and away from said mandrel to form a sheet upon said mandrel, a stripper element adopted to be moved longitudinally of the

5 mandrel and normally resting at one end thereon, means including a carriage at the other end of said stripper element, a support upon which said carriage travels and 5 means for causing a longitudinal movement of said stripper element and carriage toward and away from said mandrel.

12. A device of the kind described embodying therein a mandrel, a pair of swingable members, capable of movement toward and away from said mandrel to form a sheet upon said mandrel, a stripper element including an inverted channel member slid- 10 able on the top edge portion of said mandrel and to engage the formed sheet and to move it longitudinally off the same.

13. A device of the kind described embodying therein a mandrel, a pair of swingable members, capable of movement toward and away from said mandrel to form a sheet upon said mandrel, a stripper element adapted to be moved longitudinally of the mandrel and normally resting at one end thereon, a carriage including antifriction 25 members at the other end of said stripper element, rails upon which the antifriction elements of the carriage are adapted to travel, and means to reciprocate said stripper element with respect to said mandrel.

30 14. A device of the kind described embodying therein a mandrel, a pair of swingable members, capable of movement toward and away from said mandrel to form a sheet upon said mandrel, a stripper element adapted to be moved longitudinally of the mandrel and normally resting at one end thereon, a carriage including antifriction members at the other end of said stripper element, rails upon which the antifriction elements of the 35 carriage are adapted to travel, a reversible rotating drum arranged near the last mentioned end of said stripper element, and a flexible member associated with said drum and so arranged with respect to said stripper element as to impart a longitudinal movement in either direction to said stripper element, according to the direction of rotation of said drum.

15. A device of the kind described embodying therein a relatively high and narrow mandrel, a pair of swingable members, and means supported by said swingable members and coacting with the mandrel to hold said mandrel against swaying.

25 16. A device of the kind described embodying therein a mandrel, a pair of swingable members, and means operatively connecting said swingable members together, said last mentioned means including parts adapted to coact with the mandrel for holding said mandrel against swaying.

17. A device of the kind described embodying therein a mandrel having a groove therein, a pair of swingable members, and 50 means supported by said swingable members

and including a part adapted to enter the groove in the mandrel to hold said mandrel against swaying.

18. A device of the kind described embodying therein a mandrel having a groove 70 therein, a pair of swingable members, and means operatively connecting said swingable members together, said means including a tongue adapted to enter the groove in the mandrel to hold said mandrel against sway- 75 ing.

19. A device of the kind described embodying therein a pair of swingable members, bracket members fixed to said members and including bearing sleeves, and rigid 80 means connecting the bearing sleeves of the brackets on one member with the bearing sleeves of the brackets on the other member.

20. A device of the kind described embodying therein a pair of swingable members; bracket members fixed to said members, and having parts overhanging the edges thereof, which parts include bearing sleeves, and means connecting the bearing sleeves of the brackets on one member with the bearing sleeves of the brackets on the other member. 90

21. A device of the kind described embodying therein a pair of swingable members, bracket members fixed to said members, each bracket including a plurality of longitudinally spaced bearing sleeves, devices entering the spaces between the sleeves of opposite brackets, and pins pivotally connecting said devices to said sleeves. 95

22. A device of the kind described embodying therein a pair of swingable members, bracket members fixed to said members, each bracket including a plurality of longitudinally spaced bearing sleeves, and 105 connecting brackets also including spaced bearing sleeves aligned with the bearing sleeves of the brackets on said swingable members, and pin members pivotally connecting the aligned sleeve members together. 110

23. A device of the class described embodying a mandrel having a ridge extending part way therealong, a pair of swingable members, means providing a hinged connection for said swingable members, and means on said wing members operable in the movement of said wing members toward said mandrel for conforming a portion of a sheet to said ridge, and to that part of said mandrel beyond the same, a part of said means 115 acting to displace that portion of the sheet forwardly of said ridge into a plane above that of said ridge.

24. A device of the kind described embodying therein a mandrel having a ridge portion which terminates short of one end of the mandrel and is tapered off toward said end, a pair of swingable members, means providing a hinged connection for said swingable members, and means on said 125 130

swingable members for conforming a portion of a sheet to said ridge and its tapered portion and to displace the excess metal of the sheet beyond said tapered portion into a plane above that of said ridge portions of the mandrel.

25. A device of the kind described embodying therein a mandrel having a ridge portion which terminates short of one end ¹⁰ of the mandrel and is tapered off toward said end, a pair of swingable members, means providing a hinged connection for said swingable members, pinch bars on said swingable members and forming blocks also

on said swingable members, said pinch bars forming a part of a sheet to the ridge up to its tapered portion and said forming blocks having bevelled surfaces coacting with said tapered portions of the ridge to flatten out said sheet forward of the ridge, said sheet ¹⁵ forward of said tapered portion of the ridge being displaced upwardly by the forming blocks.

In testimony whereof, I have hereunto set my hand, this 31st day of December, ²⁵ 1924.

CHARLES GILBERT HAWLEY.
